UNITED STATES PATENT OFFICE.

JOSEPH LAPOINTE, OF WEST WARREN, MASSACHUSETTS.

RATCHET-WRENCH.

1,322,586.

Specification of Letters Patent. Patented Nov. 25, 1919.

Application filed July 27, 1917. Serial No. 183,160.

To all whom it may concern:

Be it known that I, JOSEPH LAPOINTE, a citizen of the United States, residing at West Warren, in the county of Worcester, State of Massachusetts, have invented certain new and useful Improvements in Ratchet-Wrenches; and I do hereby declare the following to be a full, clear, and exact description of the invention, such as will enable others skilled in the art to which it appertains to make and use the same.

This invention is an improvement in wrenches and has particular reference to a ratchet wrench.

15 An object of the invention is to provide an improved wrench of simple and inexpensive construction and particularly adapted to be used for turning nuts in place which are otherwise difficult of access when 20 using the ordinary wrench.

The inventive idea involved is capable of receiving a variety of mechanical expressions, one of which, for the purpose of illustrating the invention, is shown in the accompanying drawing, wherein:—

Figure 1 is a side elevation of the wrench constructed in accordance with the invention.

Fig. 2 is an edge elevation thereof.

30 Fig. 3 is a longitudinal section therethrough.

Fig. 4 is a detail perspective view of one of the socket members employed in connection with the invention.

35 Fig. 5 is a similar view of the socket operating element.

In the drawing the numeral 10 indicates the handle of a wrench having preferably formed integrally with one end thereof the 40 cylindrical head 11 provided at each end with the ratchet 12, the teeth of one end extending in opposite directions from those of the other end. The element 11 is provided with a longitudinal opening 13 in 45 which is mounted the pivot bolt 14 about which said element is adapted to rotate.

Each end of the bolt 14 supports a sleeve member 15 and since these sleeve members are substantially identical in construction 50 a description of one will suffice for both. The inner end 16 of each sleeve member is provided centrally thereof with an opening 17 for receiving the adjacent end of the bolt 14 and said inner end is also provided 55 with an annular flange 18 adapted to engage the adjacent end of the element 11 and surround an annular row of ratchet teeth 19

formed upon said end 16 and adapted for engagement with the ratchet 12 on the adjacent end of the head 11. The only difference in construction between the two sleeve members 15 is that the teeth 19 of one extend in an opposite direction from those of the other and one of said sleeve members is to be employed in threading a nut upon the bolt, while the other sleeve member is used to unscrew the nut.

Each end of the bolt 14 is screw threaded as indicated at 20 and receives thereon a washer 21 and a nut 22 which fits snugly 70 in the sleeve member, said washer 21 forming an abutment for one end of a coil spring 23 the other end of which engages the inner end 16 of the sleeve member and thereby 75 yieldably retains the teeth thereof in engagement with the teeth 12 on the head 11. It will be understood that when assembling this wrench, after the bolt 14 has been mounted in position in the head 11, the spring 23, washer 21 and nut 22 are successively placed in each sleeve member and the latter then mounted over the end of the bolt 14 so that the nut 22 will engage the threads 20 and by rotating said sleeve member said nut will be threaded upon the bolt. 80 Each sleeve is formed at its outer end to constitute a nut engaging socket and by reason of the sleeves being held by the nuts, they may be of course substituted by other sleeves to receive other sized or shaped nuts when 85 desired.

What is claimed is:—

A ratchet wrench comprising a head having a handle and an axial bore, a bolt rotatable in the bore, a sleeve for each end of the bolt having a perforated web between its ends in which the bolt is received, the sleeves at the inner ends having each a ratchet connection with the corresponding end of the head engageable in opposite directions of rotation of the head, nuts engaged with the ends of the bolt at the outer sides of the webs, and a spring within each sleeve between its web and the corresponding nut adapted to hold the sleeve with its 95 ratchet yieldably engaged, the outer ends of the sleeves having nut-receiving sockets.

In testimony whereof, I affix my signature in the presence of two witnesses.

JOSEPH LAPOINTE.
